DESIGN FOR A COMBINED PERFUME CONTAINER AND SUPPORT THEREFOR

David West, Dalegarth, Woodwaye, Oxhey, Watford, England, assignor to Saville Perfumery Limited, Watford, England, a British company

Application August 24, 1938, Serial No. 79,546
In Great Britain March 23, 1938

Term of patent 7 years

To all whom it may concern:

Be it known that I, David West, a subject of the King of England, residing at Dalegarth, Woodwaye, Oxhey, Watford, Hertfordshire, England, have invented a new, original, and ornamental Design for a Combined Perfume Container and Support Therefor, of which the following is a specification, reference being had to the accompanying drawing, forming part thereof.

The figures are respectively:

Figure 1 is a perspective view of the container and support with the top of the support removed to show the underside thereof,

Figure 2 is a perspective view showing the upper side of the top of the support,

Figure 3 is a side view of the support,
Figure 4 is a section of the support on the line 4—4 of Figure 5, showing the container in position,

Figure 5 is an under plan of the container and support with the cardboard disc (shown in Figure 4) removed,

Figure 6 is an enlarged plan view of the article.
I claim:

The ornamental design for a combined perfume container and support therefor, as shown.

DAVID WEST.
